(57) **CLAIM**

The ornamental design for an insert tool, as shown and described.

DESCRIPTION

FIG. 1 is a right, front-side perspective view of an insert tool, wherein said insert tool is inserted in a wall-mount with a bottle attached thereto.

FIG. 2 is a left, rear-side perspective view of an insert tool, wherein said insert tool is inserted in a wall-mount with a bottle attached thereto.

FIG. 3 is a front-side elevation view of an insert tool, wherein said insert tool is inserted in a wall-mount with a bottle attached thereto.

FIG. 4 is a rear-side elevation view of an insert tool, wherein said insert tool is inserted in a wall-mount with a bottle attached thereto.

FIG. 5 is a right-side elevation view of an insert tool, wherein said insert tool is inserted in a wall-mount with a bottle attached thereto.

FIG. 6 is a left-side elevation view of an insert tool, wherein said insert tool is inserted in a wall-mount with a bottle attached thereto.

FIG. 7 is a top plan view of an insert tool, wherein said insert tool is inserted in a wall-mount with a bottle attached thereto.

FIG. 8 is a bottom plan view of an insert tool, wherein said insert tool is inserted in a wall-mount with a bottle attached thereto.

FIG. 9 is a right, front-side perspective view of an insert tool.

FIG. 10 is a right-side elevation view of an insert tool.

(Continued)

FIG. 11 is a right, front-side perspective view of an insert tool, where said insert tool is inserted in a wall-mount with a bottle attached thereto.

FIG. 12 is a right, front-side perspective view of an insert tool.

FIG. 13 is a left, rear-side perspective view of an insert tool.

FIG. 14 is a front-side elevation view of an insert tool.

FIG. 15 is a rear-side elevation view of an insert tool.

FIG. 16 is a right-side elevation view of an insert tool.

FIG. 17 is a left-side elevation view of an insert tool.

FIG. 18 is a top plan view of an insert tool; and,

FIG. 19 is a bottom plan view of an insert tool.

The broken lines shown represent a wall-mount and bottle that form no part of the claimed design.

1 Claim, 14 Drawing Sheets
